Patented Apr. 28, 1959

185,006

SOFT DRINK DISPENSER

Lloyd P. Langevin, Longmeadow, Mass.

Application September 8, 1958, Serial No. 52,565

Term of patent 14 years

(Cl. D2—3)

Fig. 1.

Fig. 2.

Fig. 1 is a front perspective view of a soft drink dispenser embodying my new design; and

Fig. 2 is a front elevational view of the dispenser shown in Fig. 1.

The side not shown is substantially the same as the side shown.

I claim:

The ornamental design for a soft drink dispenser, as shown and described.
